UNITED STATES PATENT OFFICE

PERRY CUNNINGHAM, OF MADISON, SOUTH DAKOTA

GATE-FASTENER OPERATOR

Application filed March 16, 1928. Serial No. 262,118.

This invention relates to a gate fastener operator, and pertains more particularly to a gate fastener which can be operated by foot from either side thereof.

The primary object of the invention is to provide a gate fastener operator which can be easily and quickly applied to gates of common manufacture, and further aims to provide a gate fastener operator which is of simple and economical construction and one in which the parts are compactly assembled or related.

A further object of the invention is to provide a gate fastener operator in which the bottom horizontal bar of the gate is employed as a fulcrum and support for the foot operated member.

In the drawings:—

Fig. 1 is a side elevation of the invention applied to a gate of well known construction;

Figs. 2, 3 and 4 are sections on lines 2—2, 3—3 and 4—4 respectively of Fig. 1.

In proceeding in accordance with the present invention, I have shown same applied to a gate of well known construction in which latter the frame is formed of metal tubing and has a bottom bar 1, a front vertical bar 2 and a top bar 3, the frame being covered by mesh wire fabric as usual. The keeper 4 is of conventional form and is attached to a post 5, while the latch is also of conventional form and includes a substantially L-shaped spring member 6 secured at 7 to the vertical member 2 of the gate and is provided at its upper end with a U-shaped member 7 that is integral therewith and which is formed with finger grips 8 whereby the latch can be operated from either side of the gate. The rings or finger-engaging members 8 extend on opposite sides of the gate as shown in Figs. 2 and 3 and are connected by a cross bar 9. A bracket 10 is provided and which as shown in Fig. 4 is formed of a single piece of metal doubled upon itself intermediate its ends so as to

form an eye 11 which latter receives the vertical member 2 of the post therein and which is clamped to the latter by the use of a bolt 12. The free ends 13 of the bracket 10 are spread apart and receive therebetween a bell crank lever 14, the lever being pivoted to the

bracket by means of a bolt 15. A link 16 is formed with a hook shaped end 17 which latter engages over the connecting bar 9 of the latch. The outer end of the link 16 is bifurcated to receive the upper end of the bell crank lever 14 and is pivoted thereto by means of a bolt 17.

A foot engaging member in the form of a plate 18 is provided and which has a clip 19 attached thereto by means of bolts 20. As depicted in Fig. 3 of the drawings, the clip 19 embraces the lower horizontal bar 1 of the gate frame and connects the foot treadle or member 18 to the gate frame in a manner permitting oscillation of the member 18 about the lower bar 1 of the gate as a fulcrum. A pair of divergent rods 21 are employed which latter engage in an aperture 22 formed in the lower end of the bell crank lever, while the ends of the rods 21 are attached by means of nuts 22 to the outer end portions of the foot member 18.

From the foregoing it will be seen that the foot member 18 projects an equal distance from each side of the gate, thereby enabling the gate to be operated from either side thereof. In addition, it will be noted that the foot member is normally held in the horizontal position depicted in Fig. 3 by the action of the spring latch 16, which latter after operation assumes the position shown in Fig. 1, and due to its being connected to the link 16 and the latter to the bell crank lever 14 and through the rods 21 to the foot member 18, the foot member will also be restored to its normal horizontal position after release.

It will also be observed that the gate is not disturbed or altered in any way whatever, it merely being necessary in order to apply the invention to manipulate the three bolts 12, 15 and 20, 20, which enables the device to be easily and quickly applied to and removed from the gate.

What is claimed is:—

1. A gate fastener operator for use with a gate having a horizontal bottom bar and a front vertical bar and a spring latch having a cross bar, including a bracket engaged about said front bar and having spaced free ends, means to clamp the bracket to said front bar, a

bell crank lever received in the space between said free ends of the bracket, means to pivotally connect the bell crank lever to said free ends of the bracket, a link pivoted at one end to the upper end of the bell crank and having a hook at its opposite end engaged with the cross bar of the latch, a foot engaging member formed to underlie and engage said bottom bar of the gate, a clip formed to rotatably extend around the bottom bar of the gate, means to secure the clip to the foot member so as to permit both to oscillate about said bottom bar of the gate, and rods disposed on opposite sides of the gate and connected to the lower end of the bell crank lever and to opposite ends of the foot member.

2. A gate fastener operator for use with a gate having a horizontal bottom bar and a front vertical bar and a spring latch having a cross bar, including a bracket, means to secure the bracket to the front bar of the gate, a bell crank lever pivoted to the bracket, a link pivoted to the arm of the lever and having a hook engaged with the cross bar of the latch, a foot member, means to rotatably secure the foot member substantially central of its length to the bottom bar of the gate, and rods connected to the other arm of the lever and to the respective opposite ends of the foot member.

3. A gate fastener operator for use with gates having a bottom bar and a spring latch, including a foot member formed to extend on opposite sides of the bar, means directly engaged with and extending about said bar and secured to said foot member to turnably connect the latter to the bar so that the bar itself provides a fulcrum for the member, means connected to the latch to operate same, means to mount said last named means on the gate, and means connected to the operating means and to the foot member for actuating the operating means from the foot member.

4. A gate fastener operator for use with gates having a bottom bar and a spring latch, including a foot member formed to extend on opposite sides of the bar, means engaged about said bar and secured to said foot member to turnably connect the latter to the bar so that the bar provides a fulcrum for the member, a bell crank, means to pivotally mount the bell crank on the gate, means to connect one arm of the bell crank to the latch, and connections between the other arm of the bell crank and opposite ends of the foot member to actuate the latch from the foot member.

5. A gate fastener operator for use with gates having a bottom bar and a spring latch, including a foot member formed to extend on opposite sides of the bar, means directly engaged with and extending about said bar and secured to said foot member to turnably connect the latter to the bar so that the bar itself provides a fulcrum for the member,

and means between the latch and the foot member for operating the latch from the foot member.

In testimony whereof I affix my signature.

PERRY CUNNINGHAM.
